(57) **CLAIM**

The ornamental design for a golf bag strap system, as shown and described.

DESCRIPTION

FIG. 1 is a front perspective view of the golf bag strap system;

FIG. 2 is a front plan view thereof;

FIG. 3 is a rear plan view thereof;

FIG. 4 is a left side elevational view thereof;

FIG. 5 is a right side elevational view thereof;

FIG. 6 is a top elevational view thereof; and,

FIG. 7 is a bottom elevational view thereof.

The dashed lines at the top of the golf bag strap system and extending outward are included for the purpose of illustration and form no part of the claimed design. Broken lines within the golf bag strap system indicate claimed stitching.

1 Claim, 5 Drawing Sheets
